UNITED STATES PATENT OFFICE.

JOHANNES HEINRICH FRIEDRICH GÖRGES, OF BERLIN, GERMANY, ASSIGNOR
TO THE SIEMENS & HALSKE ELECTRIC COMPANY OF AMERICA, OF
CHICAGO, ILLINOIS.

STARTING DEVICE FOR ELECTRIC MOTORS.

SPECIFICATION forming part of Letters Patent No. 655,340, dated August 7, 1900.

Application filed December 31, 1897. Serial No. 665,080. (No model.)

To all whom it may concern:

Be it known that I, JOHANNES HEINRICH FRIEDRICH GÖRGES, a subject of the Emperor of Germany, residing at Berlin, Germany, have 5 invented new and useful Improvements in Starting Devices for Electric Motors, (Case No. 33,) of which the following is a specification, reference being had to the accompanying drawings, forming a part of this specification, 10 and for which Letters Patent have been granted in Germany, No. 82,016, dated October 12, 1894; in Great Britain, No. 21,141, dated November 3, 1894; in Italy, No. 37,480, dated November 10, 1894; in France, No. 15 242,309, dated October 23, 1894; in Switzerland, No. 9,356, dated October 22, 1894; in Sweden, No. 6,308, dated October 22, 1894; in Austria, No. 45/284, dated January 22, 1895; in Hungary, No. 2,858, dated May 30, 20 1895, and in Norway, No. 4,297, dated December 11, 1894.

This invention relates to rotary-current and alternating-current motors, its object being to provide means for effectively preventing 25 the sudden flow of excessive currents during the starting of the motor and before it has risen to normal speed.

The copper coils or winding of the rotating element of an alternating-current motor offers but very little resistance to the passage 30 of the current, and the electromotive force caused by a trifling loss in revolution below synchronous speed will be sufficient to produce the currents necessary for maintaining 35 the rotation of the movable element. In this respect the law laid down by Ferraris in his first treatise prevails, the law being to the effect that the percentage loss of revolutions is equal to the percentage loss of work. Since 40 with magnetism remaining constant the electromotive forces in a short-circuited armature will increase in proportion to the loss of revolutions and the heat developed in the armature will increase in proportion to the square 45 of the electromotive force, the heating effect will also increase in proportion to the square of the loss of revolutions. When, therefore, a one-horse-power motor at full capacity with a loss of revolutions of five per cent. devel-

ops in the armature about thirty-seven watts 50 of heat, due to the passage of the current, it will develop at the same magnetism with the armature at rest—that is, with a loss of revolutions of one hundred per cent.—

$$\left(\frac{100}{5}\right)^2 37 = 14,800 \text{ watts,} \quad 55$$

provided the development of such a powerful current is not prevented by some means. Thus without the provision of some starting 60 arrangement the switching in of the motor will practically short-circuit the armature, thereby permitting the flow of an excessively-large current. The powerful currents in starting will effect a very rapid starting of 65 the motor, thereby reducing the currents again to their normal value when the normal speed has been attained; but in the meanwhile the winding has been subjected to a severe shock. To overcome this objection to 70 the flow of an excessive current in starting, sliding rings and brushes have been provided to conduct the developed currents to the outside of the armature, where they are passed through a resistance adapted to be switched 75 into circuit to maintain the currents normal until speed has been attained, when the resistance may be cut from the circuit. Another remedy consists in switching resistances or reactances into the primary circuit, 80 thus lessening the tension at the terminals of the motor. The armature may also be provided with a short-circuited winding without any terminals or sliding rings.

In order to render superfluous any special 85 apparatus, it has been proposed to provide two or more separate windings upon the armature, one having a proportionally-high resistance which is always closed upon itself, while the other, of less resistance, will be closed 90 after the motor has reached a certain speed. Another method of avoiding special starting arrangements consists in switching separate divisions of the windings of the armature into circuit, whereby the starting of the motor is 95 effected in a different manner from that used during constant operation. However, in applying this method it is necessary that the

currents developed in the revolving part of the motor should always have the character of multiphase currents—that is, the currents taken by themselves should produce a magnetic field rotating with a velocity as uniform as possible and maintaining the intensity as uniform as possible. This is the case with the usual windings of the short-circuited armatures, either where the winding is closed upon itself or where it is closed through an external resistance through the agency of sliding rings. With any speed there will be produced multiphase or rotary currents, provided there are currents in the outer ring or stationary member of the motor capable of developing a rotating field. If the winding of the revolving part of the motor is switched in such a manner that the induced currents develop no tendency to produce a rotating field, it will be evident that at certain positions of the armature the moment of rotation will be a maximum, while in other positions it will be but trifling. Such a motor will therefore have dead-points. If the windings of the motor are not multiphase windings, it is possible to keep the starting-current at its proper value. It is obvious, however, that a motor having an armature with a single-phase winding will have dead-points, due to the single-phase winding, from which the armature cannot be easily started.

The object of the present invention is to provide for such a commutation or switching of the coils of the armature-winding as will effectively prevent the too sudden increase of the current when the motor is starting, while at the same time preserving completely the character of the induced currents as multiphase currents. In accordance with the present invention several windings are provided on the armature and in starting these windings are switched in such a manner as to almost entirely neutralize their electromotive forces. When speed has been attained the windings are switched in such a manner as to allow the development of the full electromotive forces of the windings to thereby produce the normal operating-current.

I have illustrated my invention in the accompanying drawings, in which Figure 1 is a diagram of a motor embodying the principles of my invention. Fig. 2 is a diagram illustrating a multiphase machine having two separate windings joined together so that the electromotive forces thereof will be opposed. Fig. 3 is a view showing the coils of the two windings severally joined together for the production of multiphase currents. Fig. 4 shows a modification of the arrangement shown in Fig. 2. Fig. 5 is a view of a modification wherein one of the windings is provided with coils divided into sections, whereby the relations between the coils of the two windings may be varied.

Like letters of reference indicate like parts in the several figures.

Referring to Fig. 1, I have shown the field-ring *b* of an induction-motor, whose coils are energized from the source of current *a*. The armature is supplied with two sets of windings *e f g* and *e' f' g'*, suitably joined to the collector-rings *c*. By means of brushes the collector-rings are in electrical connection with terminals *d*, where suitable means are provided for interchanging the connections of the said coils.

In Fig. 2 the armature of the motor shown in Fig. 1 is illustrated as provided with two windings, each winding consisting, in the present instance, of three coils joined by the star connection. One winding is provided with the three coils *e f g*, while the other winding has the three coils *e' f' g'*. The coils of the two windings are placed in the same angular positions upon the armature and are alike, except that the coils of one winding have more turns than the coils of the other winding. The corresponding ends of the coils are placed at exactly the same point upon the armature. The ends *A' a'* of the coils *e* and *e'* are connected together, likewise the ends *A² a²* of the coils *f* and *f'*, and likewise the ends *A³ a³* of the coils *g* and *g'*. The electromotive forces of the coils *e* and *e'* will thus operate against each other, as likewise will the electromotive forces of the coils *f* and *f'* and *g* and *g'*. If the coils were equal, the electromotive forces would entirely neutralize each other; but due to the fact that the coils *e f g* have more turns than the coils *e' f' g'* the former will develop larger electromotive forces than the latter, and in consequence currents will flow through the local circuits thus produced, due to an electromotive force equal to the difference between the electromotive forces induced in the coils *e f g* and those induced in the coils *e' f' g'*. The local currents thus flowing will develop a rotating field, since the coils are angularly disposed—in the present instance one hundred and twenty degrees apart—thereby producing currents which are displaced in phase one hundred and twenty degrees. The rotating field thus produced starts the armature in motion. After the armature has attained the desired or normal speed the ends of the coils may be disconnected by proper switching apparatus and the ends of the coils of the two windings may be interconnected by means of the conductors *h h' h²* and *k k' k²*, as shown in Fig. 3, whereby the motor may be caused to run as a multiphase motor having two separate windings.

It is not essential that the ends of the coils *e e'*, for instance, should be disconnected, as they may remain connected, while in addition the ends of the connected coils may be joined by the conductors *h h' h²*, as shown in Fig. 4. Thus during the starting of the motor the coils of the several windings may be so connected that the electromotive forces thereof may be opposed to produce small resultant electromotive forces capable of pro-

ducing only small currents, which are sufficient to start the motor from rest and raise the same to normal speed, after which the windings may be interconnected in multi-
5 phase arrangement, whereby the motor runs in the usual manner.

In Fig. 5 I have illustrated an arrangement whereby the resultant electromotive forces for starting the motor may be gradually increased until finally the coils of the two sets are acting in unison and developing the maximum currents at normal speed. Thus the coils $e' f' g$ are connected with the neutral or zero conductor D, as are also the coils $e' f' g'$.
15 The opposite ends of the coils $e' e'$ are joined together, as are also the opposite ends of the coils $f' f'$ and $g' g'$. The coils $e' f' g'$ are provided with a less number of turns than the coils $e f g$ and are furthermore divided into
20 sections—in the present instance the sections being four in number— $m m' m^2 m^3$, connected between terminals $l l' l^2 l^3 l^4$, a series of contact-brushes l^5 being provided adapted to be moved over the terminals and
25 joined together by the conductor D'. In starting the brushes l^5 rest upon the terminals l , in which case the whole of the winding e' is opposed against the winding e , and the resultant current flowing in the local circuit, including the windings $e' e'$, is induced by an electromotive force equal to the difference between the electromotive forces of the windings e and e' , the induced currents being thus a minimum. The coils $f' f'$ and $g' g'$
30 act in the same manner as the coils $e' e'$. When the brushes are moved to the terminals l' , the sections m are interconnected with the corresponding sections m' , and multiphase currents thus traverse the windings
35 in addition to the currents flowing in the local circuits. When the brushes are moved to the terminals l^2 , the sections m' are also connected in circuit to send multiphase currents through the interconnected windings,
40 and as the brushes are thus advanced step by step more and more of the windings are thrown into the normal interconnected arrangement for the production of multiphase currents until the brushes rest upon
45 the last terminals l^4 of the series, when all of the coils are thrown into circuit in the interconnected arrangement to produce the multiphase currents.

There are various ways besides those illustrated of switching the electromotive forces against each other while at the same time preserving the character of the currents as multiphase currents; but those shown sufficiently illustrate the nature of the present
55 invention and the manner of practicing it. In the above description it has been assumed that the coils of one winding are placed exactly on top of the corresponding coils of the other winding, and therefore the coils are
60 precisely similar except as to their relative number of turns.

Having thus described the invention, what

I claim as new, and desire to secure by Letters Patent, is—

1. In an alternating-current motor, the combination with a field portion, of an armature therefor having a multiphase winding comprising a plurality of divisions for each phase, and means for changing the connections of said divisions to vary the effective electromotive force, substantially as described. 70

2. In an alternating-current motor, the combination with a field portion, of an armature therefor having a multiphase winding comprising two sets of coils for each phase, and means for changing the interconnections thereof to vary the effective electromotive force due thereto, substantially as described. 75

3. In an alternating-current motor, the combination with a field portion having a multiphase winding, of an armature therefor having a multiphase winding comprising a plurality of divisions for each phase and means for changing the interconnections of said divisions to vary the effective electromotive force due to said winding, substantially as 85 described. 90

4. In an alternating-current motor, the combination with a field portion, of an armature therefor having a multiphase winding having a plurality of divisions for each phase, and means for connecting the said divisions in opposition to reduce the effective electromotive force and thereafter changing the connections of said divisions to remove them from opposition, substantially as described. 95

5. In an alternating-current motor, the combination with a field portion, of an armature therefor having a multiphase winding provided with two sets of coils, and means for connecting the coils of one set with the coils of the other set to have the electromotive forces due thereto opposed, thereby to decrease the effective electromotive force, and thereafter changing the connections between said sets of coils to remove them from opposition, substantially as described. 105

6. In an alternating-current motor, the combination with a field portion, of an armature therefor having a multiphase winding provided with two sets of coils, the coils of each set constituting in themselves a complete multiphase winding, and means for connecting the coils of one set with the coils of the other set to have the electromotive force due thereto opposed, thereby to decrease the effective electromotive force, and thereafter changing the connections between said sets of coils to remove them from opposition, substantially as described. 115

7. In an alternating-current motor, the combination with a field portion, of an armature therefor having a multiphase winding provided with two sets of coils, the coils of each set constituting in themselves a complete multiphase winding, the windings of one set being inductively associated with the windings of the other set, and means for connecting the coils of one set with the coils of the

other set to have the electromotive force due thereto opposed, thereby to decrease the effective electromotive force, and thereafter changing the connections between said sets of coils to remove them from opposition, substantially as described.

8. In an alternating-current motor, the combination with a field portion, of an armature therefor, a multiphase winding comprising two sets of coils for each phase, and means for changing the interconnections of said winding to create opposing electromotive force thereby to reduce the effective electromotive force in starting, substantially as described.

9. In an alternating-current motor, the combination with a field portion, of an armature therefor having a multiphase winding provided with two sets of coils, and means for connecting the coils of one set with the coils of the other set to have the electromotive forces due thereto opposed, thereby to decrease the effective electromotive force and changing the connections between said sets of coils to remove them from opposition, and varying the effective number of turns of the coils of one set, substantially as described.

10. In an alternating-current motor, the combination with a field portion, of an armature therefor having a multiphase winding provided with two sets of coils, the coils of each set constituting in themselves a complete multiphase winding, and means for connecting the coils of one set with the coils of the other set to have the electromotive forces due thereto opposed, thereby to decrease the effective electromotive force and changing the connections between said sets of coils to remove them from opposition, and varying the effective number of turns of the coils of one set, substantially as described.

11. In an alternating-current motor, the combination with a field portion, of an armature therefor, having a multiphase winding

provided with two sets of coils, the coils of each set constituting in themselves a complete multiphase winding, the windings of one set being inductively associated with the windings of the other set, and means for connecting the coils of one set with the coils of the other set to have the electromotive forces due thereto opposed, thereby to decrease the effective electromotive force and changing the connections between said sets of coils to remove them from opposition, and varying the effective number of turns of the coils of one set, substantially as described.

12. In an alternating-current motor, the combination with a field portion, of an armature therefor having a plurality of coils for each phase, and means for including the coils for each phase in opposition and varying the number of effective turns of one of the coils for each phase whereby the effective electromotive force may be reduced and varied, substantially as described.

13. In an alternating-current motor, the combination with the armature thereof having multiphase-winding coils; of means for changing the interrelation of portions of the armature-winding to create opposing electromotive forces therein, substantially as described.

14. In an alternating-current motor, the combination with the armature thereof having multiphase-winding coils; of means for changing the interrelation of portions of the armature-winding without destroying the multiphase relation of coils of the armature, to create opposing electromotive forces in the armature, substantially as described.

In testimony whereof I affix my signature in the presence of two witnesses.
